UNITED STATES PATENT OFFICE.

ROY A. DARLING, OF PELLSTON, MICHIGAN.

TOOTH-BRUSH.

1,164,597.

Specification of Letters Patent. Patented Dec. 14, 1915.

Application filed January 14, 1915. Serial No. 2,251.

To all whom it may concern:

Be it known that I, ROY A. DARLING, a citizen of the United States, residing at Pellston, in the county of Emmet and State 5 of Michigan, have invented certain new and useful Improvements in Tooth-Brushes, of which the following is a specification.

My invention relates to improvements in toilet cases and one object of the invention 10 is the provision of a toilet case and a tooth brush which can be collapsed or reduced in size to permit carrying in the pocket and which can be quickly adjusted for use and as readily collapsed and which will perform 15 its desired functions in a thoroughly efficient manner.

Another object of my invention is the provision of a toilet case embodying a container for tooth powder or dentifrice and a 20 pocket tooth brush which can be quickly adjusted for use, which will be clean and sanitary, which can be produced at the right price and which can be made of any desired and preferred material.

25 To attain the desired objects my invention consists of a toilet case embodying novel features of construction and combination of parts, substantially as shown, described and particularly defined by the claims.

30 Figure 1 is a view partly in elevation and partly in section of a toilet case constructed in accordance with and embodying my invention. Fig. 2 is an end view of the case. Fig. 3 is a view partly in elevation and partly in 35 section of a modified form of my invention, and Fig. 4 is a view of the inner end of this modified form.

In the drawings, the letter A, designates 40 the brush proper having its shank B, secured to the stem or plug E. The stem or plug E, forms what may be termed the connection by reason of its threads F, which engage the threads G, of the receiving case H, which forms a case when the brush is out of use.

In the construction shown in Figs. 1 and

2, I provide the concentric casing K, which forms a pocket or receiver L, for tooth powder or dentifrice, the end wall M, being provided with a discharge opening N, adapted 50 to register with the discharge opening O, of the pivoted cap or cover P, to cover or close the opening N, or to allow the discharge of a sufficient quantity of the powder through openings N and O to the brush, as is obvious. 55

In the form of my invention shown in Figs. 3 and 4, the container Q has discharge opening Q', at its inner end controlled by cap R, having discharge openings R', this 60 construction bringing the feed of the powder to the brush at the most desirable position.

It will be noted that both forms of my case embody the same general principle and 65 perform their function in a similar manner.

The advantages of my invention will be readily understood and it will be apparent that I provide a practical, useful and efficient toilet case and tooth brush which can 70 be easily carried in the pocket and quickly adjusted for use.

I claim:

1. In a toilet case, the combination with a tube adapted to receive a tooth brush, of a 75 perforated casing surrounding the tube and forming a container for dentifrice, said casing having a movable, perforated cap adapted to register with the perforation in the casing. 80

2. In a toilet case, the combination with a tube adapted to receive a tooth brush, of a perforated casing surrounding said tube, and a perforated, pivoted cap on the casing adapted to register with the perforations in 85 the casing to permit exit of dentifrice.

In testimony whereof I affix my signature in presence of two witnesses.

ROY A. DARLING.

Witnesses:

A. H. BUTTARS,
JOE GROBASHI.
